UNITED STATES PATENT OFFICE

154,041

DESIGN FOR A TELESCOPIC PAPER CUP DISPENSER

Gerald C. Johnson, Bronxville, and Albert A. Perelman, Brooklyn, N. Y., assignors to Lily-Tulip Cup Corporation, New York, N. Y., a corporation of Delaware

Application April 21, 1948, Serial No. 145,888

Term of patent 14 years

(Cl. D52—2)

To all whom it may concern:

Be it known that we, Gerald C. Johnson, a citizen of the United States and a resident of Bronxville, in the county of Westchester and State of New York, and Albert A. Perelman, a citizen of the United States and a resident of Brooklyn, in the county of Kings and State of New York, have invented a new, original, and ornamental Design for a Telescopic Paper Cup Dispenser, of which the following is a specification, reference being had to the accompanying drawing, forming a part thereof, wherein:

Fig. 1 is a perspective view of a telescopic paper cup dispenser embodying our new design, shown in fully extended position, indicated in conjunction therewith by broken lines being the upper end of a full stack of conical paper receptacles of the character to be dispensed therefrom;

Fig. 2 is a plan view of the device shown in Fig. 1; and

Fig. 3 is a perspective view similar to that shown in Fig. 1 but showing said device in fully collapsed position, the upper end of said stack of conical containers when nearly depleted being illustrated in broken lines.

We claim:

The ornamental design for a telescopic paper cup dispenser, substantially as shown and described.

GERALD C. JOHNSON.
ALBERT A. PERELMAN.
